UNITED STATES PATENT OFFICE.

MOSES A. WILLIAMS, OF BRAZIL, INDIANA.

TOOL FOR BORING OR REAMING DEVICES HAVING OPENINGS OF ENLARGED INTERNAL DIAMETERS.

SPECIFICATION forming part of Letters Patent No. 687,390, dated November 26, 1901.

Application filed May 23, 1901. Serial No. 61,562. (No model.)

To all whom it may concern:

Be it known that I, MOSES A. WILLIAMS, a citizen of the United States, residing at Brazil, in the county of Clay and State of Indiana, have invented certain new and useful Improvements in Tools for Boring or Reaming Devices Having Openings of Enlarged Internal Diameters, of which the following is a specification.

The object of my said invention is to provide a tool for boring or reaming in devices where a larger internal diameter is required than that of the end openings. It is frequently desirable, for example, to make turnbuckles of such form and character that a headed rod end can be inserted in one end of the turnbuckle structure, so that a swivel is formed, thus providing the turnbuckle with one swivel end and one screw end. To do this properly, one internal face of the turnbuckle needs to be machined. That variety of turnbuckles illustrated, for example, in the Charles H. Williams patent, No. 373,871, dated November 29, 1887, while of a superior character as an ordinary turnbuckle, has heretofore not been practicable for a turnbuckle of the variety stated, for the reason that no practicable means existed for machining the surface upon which the head of the swivel should rest.

It is the object of my present invention to provide a tool or reamer by means of which such machining may be effectively and economically performed, thus adapting turnbuckles of the variety in question to be fitted in the manner stated or performing other similar work.

Said invention consists of a tool adapted to the purpose, as will be hereinafter more particularly described and claimed.

Referring to the accompanying drawings, which are made a part hereof, and on which similar reference characters indicate corresponding parts, Figure 1 is a side elevation of a turnbuckle-blank being operated upon by one of my improved tools, thus illustrating one of the uses of said tool; Fig. 2, a central vertical sectional view thereof, the cutting member of the tool being also shown in section; Fig. 3, a longitudinal sectional view of the finished turnbuckle after the tool has done its work and been removed, the po-

sitions of the rod ends therein being shown by means of dotted lines; Fig. 4, a horizontal sectional view as seen when looking downwardly from the dotted line 44 in Figs. 1 and 2; Fig. 5, a view similar to Fig. 4, with the cutting-tool turned at right angles with its former position; Fig. 6, a horizontal sectional view through the turnbuckle at a point indicated by the dotted line 66, showing the interior of the turnbuckle end after the same has been machined and the work of my improved tool is completed and the tool itself removed; Fig. 7, an end elevation of the bottom end of the cutting-tool separately; Fig. 8, a side elevation of the cutting-tool and guide-pin separately on an enlarged scale; Fig. 9, a side elevation of the guide-pin separately; Fig. 10, a top plan of the cutting-tool separately, and Fig. 11 a bottom plan of the cutting-tool separately.

The turnbuckle-blank 15, in connection with which the use of my improved tool is illustrated, is made and finished in the ordinary manner, with its ends turned off and the perforations therein finished by boring or drilling. The cutting-tool 16 is then inserted therein through one of the open sides thereof, said tool having two of its sides flattened to enable it to enter, being otherwise circular in cross-section and of the diameter which it is desired the finished bearing for the headed bolt end shall be. A guide-pin 17 is secured to the point of this cutting-tool 85 and is of approximately the same diameter as the perforation in the end of the turnbuckle, and is adapted to enter and be guided by the said perforation. As the tool is driven downward the guide obviously maintains the tool in a central position in the blank, so that the resulting seat is the same on all sides of the perforation. This guide, while rigid with the cutting-tool, is removable therefrom, so that it may be removed when it is necessary to sharpen said tool. The union between these two parts is conveniently effected by forming a screw-threaded perforation in the lower end of the cutting-tool and providing a correspondingly-screw-threaded stud on the upper end of the guide, the screw-threads being formed reversely to the travel of the tool, so that the tool and guide will not become disconnected in use. After the cutting-tool

and its guide are in place a shank 18 is inserted through the perforation at the opposite end of the turnbuckle-blank and enters a suitable perforation in the upper end of the 5 cutting-tool, the formation being such (it is shown as square) that while the shank can be readily inserted and removed longitudinally it will, when inserted and revolved, also revolve the cutting-tool. This shank at its 10 outer end is adapted to be grasped by a chuck and driven by an ordinary drill-press or lathe in the ordinary and well-known manner of driving tools in such machines.

While this tool has been especially designed 15 for finishing swivel-head seats in turnbuckle-blanks and has been illustrated as it appears when performing that work, it may be used wherever an enlarged internal diameter is required, as will be readily understood, and 20 I desire to be understood as claiming it for any use of which it is capable.

Having thus fully described my said invention, what I claim as new, and desire to secure by Letters Patent, is—

25 1. A tool for boring or reaming in devices having openings of enlarged internal diameters comprising a cutting-tool adapted to be inserted within the body of the turnbuckle-blank, a guide on the cutting end of said tool 30 adapted to enter the perforation in one end of the turnbuckle-blank, and a shank adapted to be inserted through the perforation in the other end of the turnbuckle-blank and engage with and drive said cutting-tool, said 35 tool as a whole being adapted to be driven

by an ordinary machine, as a drill-press or lathe, substantially as and for the purpose set forth.

2. The combination in a tool for boring or reaming devices having enlarged internal diameters, of a cutting-tool having certain of its sides cut away whereby it is capable of entering through the exterior openings of such devices into the enlarged internal chamber therein, a guide for holding said cutting- 40 tool to central position removably secured to the cutting end thereof, and a driver adapted to removably engage with the other end.

3. The combination in a tool for boring or reaming devices having enlarged internal diameters provided with one or more openings of less diameter extending to the outside, of a cutting-tool one diameter whereof is substantially equal to the internal diameter of the device to be bored or reamed while the 55 other is reduced sufficiently to permit it to enter through the openings extending to the outside, a guide extending out centrally from the cutting end of the cutting-tool, and a driving shaft or stem adapted to engage with 60 the opposite end of said cutting-tool, said guide and said shaft or stem being of smaller diameter than the body of the cutting-tool.

In witness whereof I have hereunto set my hand and seal, at Brazil, Indiana, this 20th 65 day of May, A. D. 1901.

MOSES A. WILLIAMS. [L. s.]
